UNITED STATES PATENT OFFICE

FREDERICK C. HERSEE, OF WATERTOWN, AND NATHANIEL T. WILEY, OF SOMERVILLE, MASSACHUSETTS, ASSIGNEES, BY DIRECT AND MESNE ASSIGNMENTS, TO F. C. HERSEE COMPANY, OF WATERTOWN, MASSACHUSETTS, A CORPORATION OF MASSACHUSETTS

LAMP SOCKET AND TERMINAL THEREFOR

Application filed June 15, 1927. Serial No. 199,019.

This invention relates to electric lamp sockets and terminals therefor, and aims to provide improved means for connecting the lamp bulb with a source of electrical energy. 5 The invention is more particularly, but not exclusively, designed for use in respect to head lights and tail lights of automobiles, wherein automatically adjustive contact terminals are employed to establish circuit connection with the lamps.

The invention will best be understood from a description of one selected embodiment thereof illustrated in the accompanying drawings, and wherein

15 Fig. 1, is a vertical longitudinal section showing the invention operatively assembled in association with a lamp bulb;

Fig. 2, a similar sectional view of the terminal parts disassembled and conveniently grouped in the normal order of their assembly;

Fig. 3, a side view of the terminal with feed cable operatively attached thereto; and

25 Fig. 4, a cross sectional view of the invention on the line 4-4 of Fig. 1, looking in the direction indicated by the arrow.

In carrying out the invention in the form shown a lamp bulb 10 having the usual metallic base 11 provided with contact element 12 and detachably mounted in any approved manner in a holder 13 is selected for purposes of illustration, although it should be understood that it is not our intention to limit the application of our invention exclusively to lamp bulbs or to the particular form of mounting or holder herein illustrated.

The present holder 13 is of tubular metal construction having an open front end to receive the lamp bulb and a closed rear end provided with a central opening 14 therein to receive a conductor 15 for connecting the lamp bulb with a suitable source of electrical energy. The lamp bulb may be secured in position by means of lugs 16 laterally provided on the base 11 and adapted to register with angular slots 17 provided on the margin of the holder. Said holder is preferably formed in detachably connected sections. In the present instance, the rear portion of the holder constitutes a separate detachable member

18 which is fitted into the main portion 13 and forms an extension thereof, suitable locking means being provided for securing the parts together, as, for example, by bosses 19 formed at opposite points on the wall of the rear portion and registering with corresponding marginal slots 20, similar to the slots 17 on the front portion of the holder.

Seated in the front end of the rear holder portion 18, we provide an annular insulation 60 terminal carrier 21, which extends forward into the main portion 13 and is suitably enlarged within the latter to engage the walls thereof. The conductor 15 is extended forward within the holder into the bore 22 of the carrier and supports on its front end a metal terminal 23 extending through and beyond the carrier for engagement with the contact 12 of the lamp bulb. The terminal 23 is recessed centrally in its rear end to receive the wires 24 of the cable 15, which are soldered or otherwise permanently secured thereto, and has a reduced front extension portion 25 formed for normal engagement with the contact element 12. This method of attachment of the terminal to the cable permits the axial centres of these parts to be brought into alignment, and, as the maximum diameter of the terminal is substantially the same as the diameter of the cable 80 they may be readily drawn in assembled relation through the reduced opening 14 in the rear end of the holder and also through such other openings (not shown) as are commonly provided in other parts for the support 85 of the cable or cable harness. Moreover, the occasional pull exerted on the terminal by the cable in retraction is thus directed in a straight line and avoids any side thrust such as occurs when the cable wires are laterally attached to the terminal, as is commonly practised.

Combined means are provided for actuating the terminal forward and for opposing and limiting rearward displacement thereof. These means include a detachable sleeve member 26 mounted on the extension portion 25 and terminating at its front end in an apertured head 27 forming interior and exterior shoulders 28, 29, said end, including 90 100

the head 27, being bifurcated by a transverse slot 30, thereby presenting opposing semi-circular parts susceptible of limited movement relatively to each other. In mounting the sleeve member on the terminal, the extension portion 25 is first introduced into the rear end of the sleeve member and thrust forward through and beyond the bifurcated portion, thus initially spreading the head 27 which again resumes its normal outline as the terminal continues to advance, permitting the parts of the head to spring back into their original position when the interior shoulders 28 drop into an annular recess 31 provided on the terminal near its front end. This locking engagement of the sleeve member with the terminal normally effectually prevents lengthwise displacement of the former in either direction and possesses obvious advantages over the usual practice of soldering or otherwise permanently uniting the parts and preventing their disassembly when necessary.

Mounted upon and closely engaging the front end of the sleeve member 26 is an expansion spring 32 bearing at one end against the exterior shoulders 29 of the sleeve member and at the opposite end against the apertured bottom of a socket member or bushing 33, which is fitted into the bore of the carrier 21 around the spring and provided at its front end beyond the bore with an exterior flange 34 adapted to bear against the face of the carrier. Said spring and socket member are cooperatively adapted to limit retraction movements of the terminal induced by force applied to the cable 15 beyond the holder 18, said spring tending to actuate the terminal forward to its forward limit of movement and to maintain the terminal normally in engagement with the contact element 12 on the lamp bulb. In originally mounting the spring 32 and socket member 33 on the sleeve member, the rear end of the latter is preferably introduced through the front ends of the former, whereupon the rear end of the sleeve member may be flared out, as at 35 (Fig. 1), to prevent rearward displacement of these parts. The shoulders 29 of the sleeve head 27 are preferably slightly inclined on their rear face whereby the engaging spring 32 has a tendency to force the opposing parts of the head toward each other, thus preventing the interior shoulders 28 from leaving the terminal recess 31 and consequent displacement of the sleeve. To remove the sleeve, therefore, from its mounting it is first necessary to slide the spring back a sufficient distance at least to clear the bifurcated portion of the sleeve and thus allow the head 27 freedom for spreading.

It will be understood that our invention is susceptible of various modifications in embodiment and application without departing from the generic purpose and objects thereof.

illustrated in the foregoing specification, and all coming within the scope of the appended claims.

We claim as our invention:

1. In a terminal, in combination, a support having a bore therethrough, a conductor extending into said bore, a terminal member secured at one end to said conductor within said support and having a reduced portion at the opposite end extending through and beyond said support, a sleeve mounted on and detachably secured to said terminal reduced portion and having a head arranged beyond said support, a spring mounted on the sleeve and engaging said head, and a support-engaging bushing enclosing said spring and providing an abutment for the rear end of the spring. 75

2. In a device of the class described, in combination, a tubular housing for supporting at one end a lamp bulb having a contact element thereon, a conductor extending into the opposite end of the housing, a terminal on the conductor within the housing for engagement normally with said contact element, a carrier fixed in the housing for enclosing and supporting said terminal, a sleeve movably mounted on the terminal within the carrier, locking means for detachably securing the sleeve on the terminal, an expansion spring carried on the sleeve for actuating the terminal toward the contact element, and a bushing fitted in the carrier and surrounding said sleeve and spring and providing an abutment for the spring. 85

3. In a terminal, in combination, a stem member having a recess at or near one end, a sleeve carried on the stem member and having a head at one end, said sleeve being bifurcated a portion of its length including said head, said head having an internal portion extending into said recess, and an external portion forming an abutment and a coil spring surrounding said sleeve and bearing in operative position at one end against said abutment. 95

4. In combination with a lamp socket for the support of a lamp bulb, a carrier fixed in said socket and having a bore therethrough to receive a conductor, a terminal for attachment at one end to the conductor and adapted to be extended with a portion of the conductor freely into and withdrawn from the bore of said carrier, said terminal having a reduced portion forming a stem member for engagement normally with the lamp bulb and provided with a groove at or near its outer end, terminal actuating means surrounding said stem member and including a sleeve detachably mounted thereon within the carrier and adapted to be slid onto and off the terminal at its front end, said sleeve having internal and external shoulders at its front end and being bifurcated a portion of its length, said internal shoulder of the sleeve being 110

adapted to snap into said groove on the terminal, a bushing movably fitted into the bore of the carrier surrounding a portion of the terminal, said bushing having an external flange 5 at its outer end for engaging the face of the carrier and an internal flange at its opposite end, and a coil spring within the bushing and surrounding the terminal, said spring being seated at its inner end on the internal flange of the bushing and adapted to bear at its front 10 end on the external shoulder of said sleeve.

5. In a device of the class described, in combination with a holder and a lamp bulb having a contact element thereon and mounted 15 in said holder, a carrier mounted in the holder and having a bore therethrough, a conductor extending into said bore and having a terminal extending through and beyond said bore and into position for engagement 20 with said lamp bulb, said terminal being retractile by and with the conductor out of contact with the lamp bulb, and means mounted on the terminal and cooperating with the terminal and said carrier for normally maintaining contact between the terminal and said 25 contact element on the lamp bulb, said means including a sleeve slidably fitted on the terminal and having an abutment thereon, means on the sleeve coacting with means on the terminal detachably locking the sleeve on the 30 terminal, a bushing fitted in the bore of the carrier and freely surrounding said sleeve and having an abutment arranged opposite the abutment on the sleeve, and an expansion 35 spring surrounding said sleeve within said bushing and engaging said abutments.

6. In combination with a carrier having a bore therethrough, an insulated conductor having a bared end extending freely into one 40 end of said bore, a stem member bored at one end to receive the bared end of the conductor and extending at its opposite end through and beyond the carrier, a sleeve loosely carried on the stem member and having abutments at 45 opposite ends, means for detachably locking the sleeve on the stem member, a bushing carried on the stem member and fitted into the bore of the carrier and freely surrounding a portion of said sleeve, said bushing having an annular external abutment at its outer end 50 for engagement with the carrier and an annular internal abutment at its inner end intermediate the abutments on the sleeve, and a coil spring surrounding a portion of the sleeve 55 within the bushing for engaging the forward abutment of the sleeve and the internal abutment of the bushing.

In testimony whereof, we have signed our names to this specification.

60 FREDERICK C. HERSEE.
NATHANIEL T. WILEY.
